UNITED STATES PATENT OFFICE

EDWARD CURRIE, JR., OF TORONTO, ONTARIO, CANADA, ASSIGNOR OF ONE-HALF TO ROBERT JOHN QUIGLEY, OF SAME PLACE.

NECKTIE-HOLDER.

SPECIFICATION forming part of Letters Patent No. 390,571, dated October 2, 1888.

Application filed November 2, 1887. Serial No. 254,087. (No model.)

To all whom it may concern:

Be it known that I, EDWARD CURRIE, Jr., of the city of Toronto, in the county of York, in the Province of Ontario, Canada, merchant, 5 have invented a certain new and useful Improved Necktie-Holder, of which the following is a specification.

The object of the invention is to design a light, neat, cheaply-made, and easily-adjusted 10 necktie-holder, by which the ties may be supported and properly displayed, and which will expose the name of the dealer printed upon the inside of the neckband; and it consists, essentially, of a spring or springs connected to 15 a suitable support and arranged to fit into the neckband of the tie when the latter is fastened, so that the said spring or springs shall hold by the force of their expansion the said neckband in such a manner that the tie, which is 20 attached to or forms part of the neckband, is properly displayed, and the name of the dealer, which is usually printed on the band, is suitably exposed.

Figure 1 is a perspective view of my necktie-holder, showing it attached to a movable stand. 25 Fig. 2 shows it formed to fit onto a counter or shelf. Fig. 3 shows it formed to fit onto a rod or bar. Fig. 4 shows it fitted onto a counter or shelf, the spring portion being shaped so as 30 to hold the neckband of the tie in a circle. Fig. 5 is a back view of my necktie holder applied.

A represents legs, which are either attached to a stand, B, as shown in Fig. 1, or have a loop, 35 C, formed in them to fit onto a shelf or rod, as shown in either Fig. 2, 3, or 4. The legs A may be bent either as shown in Figs. 1, 2, and 3, or as shown in Fig. 4, and either one or both of the legs may be made to spring, so that 40 when the two legs are pressed together the tension of the spring may be utilized to support the article compressing it.

It will be noticed that in Figs. 2 and 4 the loop C is formed so as to fit into the ledge of a counter or onto a shelf, supporting the legs 45 A in a vertical position.

In Fig. 3 I show the loop C formed to fit onto the rod D. This latter form permits the legs A to be adjusted to various angles, so that the tie E, which they support, may be displayed 50 at any angle desired. The ends of the neckband or portion of the tie E which is intended to pass around the neck must, of course, be knotted or otherwise fastened together before it is applied to my holder, and the loop thus 55 formed by the tie or its band must be of such a size that the legs A will be pressed together when the loop formed by the tie is fitted over them.

I do not confine myself to the exact form of 60 the legs A shown.

In Fig. 5 I show the loops C bent together to grasp the end of the necktie for the purpose of connecting the said necktie to the holder, so that it will follow the same to any angle at 65 which it may be set on the rod D.

What I claim as my invention is--

1. As an improved article of manufacture, a necktie-holder consisting of a single piece of wire bent to form legs A, a loop, C, in said 70 legs, and spring-arms to fit into the loop of a tie, substantially as shown and described.

2. As an improved article of manufacture, the necktie holder described, composed of a single piece of metal bent to form legs A, 75 spring-arms at the free ends of said wire to fit the neck-loop of a tie, and a loop, C, in said legs bent together, substantially as shown, and for the purpose specified.

Toronto, October 5, 1887.

EDWARD CURRIE, JR.

In presence of--

DONALD C. RIDOUT,
CHARLES C. BALDWIN.
